UNITED STATES PATENT OFFICE

98,246

DESIGN FOR A TEXTILE FABRIC

Curt Erwin Forstmann, Montclair, N. J.

Application March 11, 1935, Serial No. 55,831

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure is a plan view of a piece of the textile fabric embodying the design of the present invention.

The design is a stripe resulting in the novel spacing in the warp of "flame" yarns, that is to

say, yarns having nodes or enlargements at intervals, the repeated motif comprising three pairs of "flame" yarns narrowly spaced in the pair, three relatively wide background stripes delineated by single "flame" yarns, one pair of narrowly spaced "flame" yarns and another relatively wide background stripe.

The repeated unit is indicated between the broken lines shown in the drawing.

I claim:

The ornamental design for textile fabric as shown and described.

CURT ERWIN FORSTMANN.
